DESIGN FOR A CONTAINER OR SIMILAR ARTICLE

Wallace E. Garvey, Salem, N. J., assignor to Salem Glass Works, Salem, N. J., a corporation of New Jersey

Application January 3, 1935, Serial No. 54,690

Term of patent 14 years

To all whom it may concern:

Be it known that I, Wallace E. Garvey, a citizen of the United States, residing in Salem, county of Salem, State of New Jersey, have invented a new, original, and ornamental Design for a Container or Similar Article, of which the following is a specification, reference being had to the accompanying drawing, forming a part thereof.

The figure is a perspective view of a glass container, illustrating my new design.

I claim:

The ornamental design for a container or similar article, substantially as shown.

In witness whereof, I have hereunto affixed my hand and seal, this 29th day of December, 1934.

WALLACE E. GARVEY.
